UNITED STATES PATENT OFFICE.

WILLIAM CHARLES DOWD, OF QUINCY, ILLINOIS.

MULTISTAGE PUMP.

Application filed August 15, 1924. Serial No. 732,282.

My invention relates to improvements in multi-stage pumps and it consists in the combinations, constructions, and arrangements herein described and claimed.

5 An object of my invention is to provide a pump of the character described in which means is provided for overcoming the objection found in the ordinary type of water pump by the improper converting of the 10 velocity of the water after it leaves the impeller rim into pressure before it reaches the eye of the next impeller.

A further object of my invention is to provide a pump in which means is provided 15 for causing the velocity of water as it leaves the impeller to decrease, thereby increasing the pressure as the water approaches the eye of the next impeller, or delivery port.

A further object of my invention is to 20 provide a pump of the character described in which the standard type of propeller or propeller shaft may be employed.

A further object of my invention is to 25 provide a pump of the character described in which a novel arrangement of the return water pipe from the automatic balance to the suction end of the pump is provided. This pipe is installed in such a manner as 30 to preclude the presence of eddy currents set up by the rotating water in the suction end of the pump.

A further object of my invention is to 35 provide a pump of the character described that is extremely efficient in operation, simple in construction and which is thoroughly practical for the purpose intended.

Other objects and advantages will appear 40 in the following specification, and the novel features of the invention will be particularly pointed out in the appended claim.

My invention is illustrated in the accompanying drawings forming a part of this application in which—

45 Figure 1 is a sectional view of an embodiment of my invention.

Figure 2 is a top plane view of the lower portion of the pump casing.

Figure 3 is an end elevation of the mechanism illustrated in Figure 1.

50 Figure 4 is a sectional view along the line 4-4 of Figure 1, and

Figure 5 is an irregular sectional view of the pump, showing the peculiar cross sectional contour of the adjacent stages and 55 volute.

In carrying out my invention I make use of the ordinary type of impeller shaft 1 rotatably mounted in bearing portions 2 of a pump casing A. The casing A is composed of an upper and lower section 3 and 4, respectively. These sections are secured to one another by the provision of bolts 5 projected through aligned openings 6 and contacting flange portions 7 of the sections 3 and 4.

The casing A is divided into three chambers in the present form of my invention, which I shall hereinafter refer to as stages. These stages are indicated at 8, 9, and 10, respectively.

50 Impellers 11, 12, and 13 are carried by the shaft 1, and are disposed within the stages 8, 9, and 10, respectively of the casing A. These impellers are provided with an eye portion 14 for the purpose of permitting the entrance of water therethrough, so that it may be delivered at a high velocity through delivery openings 15 at the rim of the impeller. The lower section 4 of the casing A has a port 16 at one end thereof, and a delivery port 17 at the opposite end. The delivery port is smaller in diameter than the suction port 16, so that water delivered through the port 17 must necessarily travel at a substantially greater velocity 55 than the entrance water would through the suction port.

60 In Figure 4 I have shown a sectional view of that portion of the casing adjacent to the delivery port, and in dotted lines indicated at 18 I have shown the approximate sectional contour of this part of the pump.

With reference to Figures 1 and 2 it will be noted that an irregular space or double volute 20 is provided, which conducts water 65 from the adjacent impeller chamber through, first, relatively small conducting portions 21 thence through gradually increasing portions to that space immediately behind the next impeller, where the conducting area of the volute is relatively large.

70 The purpose of this construction is to increase the pressure of the water as it enters the eye of the impeller, thus accomplishing a conversion of the velocity of the water 105 after leaving the eye of the impeller in its travel to the eye of the next impeller.

The convolutions of the volutes 20 are shown most clearly by a study of Figures 1 and 2, together, and the contour of the sec- 110

tions through the volutes may be seen by inspection of Figure 5.

In Figure 5 the double volutes between each of the chambers is clearly shown, and it will be noted that water is delivered to the eye of the impeller through the volutes in opposite directions and at a diminishing velocity.

Means for preventing a whirl of the two volumes of water conducted through the volutes at the eye of the adjacent impeller is provided in a bushing 30 having vane portions 31 extending toward the eye of the adjacent impeller. These bushings are disposed in the wall between the chambers 8 and 9 and the adjacent volutes and serve to gather the two volumes of water at the eye of the succeeding impeller.

Another important feature of my invention consists in the provision of a return water pipe 22 for conducting water from the balance chamber 23 at the delivery end of the pump to the suction chamber 23' at the suction port 16. The connection of the return pipe 22 with the suction chamber 23' is shown at 24, and is disposed in such a position that the eddy current set up by the returning water through the return pipe, ordinarily found in centrifugal pumps, is not present. In other words, it brings the water back into the suction end of the pump from the balance chamber in such a position that the incoming water from the suction port 16 draws in the water from the returning pipe 22 without any disturbance in the flow of water to the first impeller, 15.

From the foregoing description of the various parts of the device, the operation thereof may be readily understood. In operation my improved multi-stage pump operates much as the ordinary type of multi-stage pump, with the exception that the use of diffusion vanes is eliminated and a more efficient means is employed for converting the velocity of the water as it leaves the rim of the impeller to a higher pressure and a lower velocity when it reaches the eye of the next impeller. This is accomplished solely

by the novel construction of the volutes 20 disposed between the chambers 8, 9, and 10. 50

It has been found by actual operation, using the same impellers and impeller shaft, that my improved casing embodying the volute construction is 6% more efficient than the ordinary type of single volute pump. 55

Another important advantage is obtained in the removal of water from the automatic balance chamber 23 to the suction end of the pump without disturbing the movement of water to the first impeller. This is accomplished by connecting the return pipe with the suction chamber 23' at a point in the lower wall of the chamber just forward of the impeller shaft and in that portion of the chamber which is greatest in capacity. 60

I claim:

A centrifugal pump comprising a casing, a plurality of impellers, means for actuating said impellers, said casing having a double volute leading from one impeller to the eye of the next impeller, said double volute consisting of two passageways, one passageway starting at a point diametrically opposite to the other making a complete circle and terminating adjacent the eye of the next impeller, the terminating point being disposed diametrically opposite the terminating point of the other passageway, said passageways increasing in area as they approach the eye of the next impeller, whereby a decreasing of 70 velocity and increasing of pressure of the water is effected, means for preventing whirling of the water as the two streams of water from the two volutes merge into one stream, said means comprising a bushing 75 disposed adjacent each of said impellers, and deflecting vanes integral with said bushings and having concave surfaces merging into each other at their adjacent extremities for directing the flow of the two volumes of 80 water in one direction, whereby the two volumes of water will merge into one volume and be conducted into the eye of the 85 next impeller. 90

WILLIAM CHARLES DOWD.
